[57] CLAIM

The ornamental design for a portable boat boarding ramp, as shown and described.

DESCRIPTION

FIG. 1 is a side perspective view of a portable boat boarding ramp, in accordance with the present design; FIG. 2 is a bottom elevational view of said portable boat boarding ramp;

FIG. 3 is a top elevational view of said portable boat boarding ramp;

FIG. 4 is a handrail side elevational view of the portable boat boarding ramp;

FIG. 5 is the opposite side view of the portable boat boarding ramp;

FIG. 6 is a front elevational view of the portable boat boarding ramp;

FIG. 7 is a rear elevational view of the portable boat boarding ramp; and

FIG. 8 is a perspective of an exploded view of the portable boat boarding ramp.

FIG. 1

FIG. 2

FIG. 3

FIG. 4
